BY
Richard Blewer,
ATTORNEY.

UNITED STATES PATENT OFFICE.

HENRY A. WILLIAMS, OF KINSTON, NORTH CAROLINA.

HEEL ATTACHMENT FOR SHOES.

1,343,602.

Specification of Letters Patent. Patented June 15, 1920.

Application filed March 27, 1919. Serial No. 285,546.

To all whom it may concern:

Be it known that I, HENRY A. WILLIAMS, a citizen of the United States, residing at Kinston, in the county of Lenoir and State 5 of North Carolina, have invented certain new and useful Improvements in Heel Attachments for Shoes, of which the following is a specification.

This invention relates to improvements in 10 heels for shoes and the primary object of the invention is to provide a light, durable and cheap metallic heel especially adapted to be held in position without rivets, nails, pegs or other similar fastening elements and 15 which can be readily removed when the shoe becomes worn, so that the heel may be attached to a new shoe.

Another object of the invention is to provide a removable shoe heel constructed 20 entirely of metal and comprising two separate co-acting sections which form the complete heel when the sections are assembled and which are constructed to be readily separated when the heel is to be detached.

25 A further object of the invention is to provide a device of this character which consists of comparatively few parts and is simple in construction but durable and well adapted to withstand the rough usage to which devices of this character are ordinarily subjected.

30 For a full description of the invention and the advantages and merits thereof reference is to be had to the following description and accompanying drawings, in which:—

Figure 1 is a fragmentary elevation of a shoe showing the invention applied thereto.

Fig. 2 is a perspective view of a portion 40 of the heel.

Fig. 3 is a perspective view of a body portion of the heel, and

Fig. 4 is a section taken on the line 4—4 of Fig. 1.

45 Referring to the drawings in which is illustrated the preferred form of my invention, in which like numerals of reference indicate like or corresponding parts throughout the several views, the body 1 comprises a band of metal 2 adapted to be bent to form the body of the heel. The upper marginal edge of the band is provided with inturned lugs 3 which form retaining flanges adapted 50 to engage the only lift A attached to the heel portion of the shoe as shown in Fig. 4. The marginal edge of this lift extends out-

wardly in the usual manner after the body of the shoe has been sewed or secured to the lift and thereby forms a convenient projecting portion to receive the retaining flanges 60 for holding the body portion of the removable heel in position. Projecting upwardly at certain intervals on the upper marginal edge of the band are the lugs 4 which embrace the heel portion of the shoe body as 65 shown in Fig. 1 when the device is in position. At each end of the band I have provided a spur 5 which projects inwardly and the lift A is notched as indicated at 6 to receive these spurs. The ends of the band are 70 provided with extensions which are bent inwardly toward each other and form clips 7 each having a slot 8 to act in maintaining the heel plates 9 in position. The heel plate 9 comprises a metallic plate shaped to conform to the shape of the heel body and having its marginal edge provided with upturned lugs 10 which form a flange extending around the edge of the heel plate and adapted to embrace the band as shown to 80 advantage in Figs. 1 to 4 of the drawing.

At the rear end the plate 9 is provided with a tongue 11 which may be bent to extend through the slot 12 intermediate the ends of the band 2 thereby providing a hinged connection for the plate and the body portion of the heel and permitting the plate to be swung toward and away from the heel when being attached or detached. At the forward edge of the plate is an upstanding clip 90 flange 13 which has its upper end provided with a projection 14 adapted to be received in a notch formed in the bottom of the shoe at this point. The ends of the flange 13 are provided with hooks 15 shaped to be received in the slots 8 when the parts are assembled.

When being mounted in position, the band is opened sufficiently to extend around the lift A whereupon the ends of the band are held in the finger of the hand while the heel plate being hingedly connected to the band is swung upwardly to operative position whereupon the ends of the band will be pressed inwardly and the hooks 12 will snap into engagement with the slots 8 on the clips 7 thereby holding the parts in assembled position and preventing casual or accidental displacement of the heel from the shoe. The tendency of the band to swing outwardly causes the clips to maintain a tight 110 engagement with the hooks 15 so that the heel will not be displaced. In order to re-

move the heel from the shoe it is merely necessary to press inwardly on the ends of the band so that the clips disengage the hooks whereupon the heel plate may be 5 swung downwardly on its pivot and the band may be opened sufficiently to disengage the lift A thereby permitting the heel to be readily removed. With this construction it is possible to mount the heel on any 10 pair of shoes in which the heel or ordinary rubber heel has been removed and inasmuch as the heel will wear considerably longer than the ordinary shoe heel or shoe it will be possible to use the heels repeatedly on new 15 shoes.

The foregoing description and accompanying drawings have reference to what might be considered to be the preferred or approved form of my invention. I desire it to 20 be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

1. A shoe heel comprising a removable body portion and a removable heel plate attached to the body portion, and a heel hingedly mounted on the body portion and means to releasably hold the heel plate in engagement with the body portion.

2. A heel structure comprising a remov-

able band having clips at its ends, means to 35 retain the band in position on the shoe, a plate hingedly mounted on the band and hook members adapted to be engaged with the clip members to releasably hold the heel plate in engagement with the said band. 40

3. A removable heel adapted for attachment to a shoe comprising a band having a retaining flange adapted to engage a portion of the shoe, clip members formed on the ends of the band, a removable heel plate 45 hingedly connected to the band, and hook members carried by the heel plate and adapted to engage the said clip members to maintain the band and heel plate in assembled position when the band is attached to the 50 shoe.

4. A removable heel adapted for attachment to a shoe having a lift mounted thereon, a band adapted to embrace the lift and provided with retaining flanges overlapping the lift to retain the band in position, clip members formed at the end of the band, a heel plate provided with a tongue adapted for pivotal connection with the band approximately intermediate the ends thereof 60 whereby the said heel plate may be swung on the band, and hook members carried by the forward end of the heel plate to engage the said clips for maintaining the band and heel clip in position on the heel. 65

In testimony whereof I affix my signature.

HENRY A. WILLIAMS.
